DETACHABLE RADIATOR TUBE

Filed Jan. 11, 1928

Inventor:

Alfred Edwin Hughes
By his Attorney: Walter Gunn

UNITED STATES PATENT OFFICE

ALFRED EDWIN HUGHES, OF STOCKPORT, ENGLAND

DETACHABLE RADIATOR TUBE

Application filed January 11, 1928. Serial No. 246,063.

This invention relates to detachable tubes for radiators and the like and has for its object an improved detachable tube which is easily fitted and removed and which is adapted to provide a radiator of increased efficiency.

In tubular radiators the tubes are arranged between headers or containers which hold the bulk of the water and in which are provided the necessary connections for the usual flexible tube connections to the water jacket of the engine. The circulation of the water in the system is downwardly through the radiator tubes and as the aggregate cross-sectional area of such tubes is always considerably larger than the cross-sectional area of the connectors, there is a tendency for those in the centre of the radiator and nearest to such connectors to receive the greater part of the circulation thus reducing the cooling efficiency of the radiator.

According to the present invention an improved detachable radiator tube is provided having a restriction at either or both ends whereby a more even distribution of the circulation is obtained, the water remaining longer in the tubes and more efficient cooling resulting.

The accompanying drawing illustrates the invention in which:—

Fig. 1 is a part sectional elevation of one form of detachable radiator tube.

Figs. 2, 3, 4, and 5 are sectional elevations of an end of a tube of modified constructions.

As illustrated in Fig. 1 the detachable radiator tube comprises a thin brass tube *a* having at its upper end a fixed collar *b*, sliding collar *c* and spring *d* and at its lower end a collar *e*. The tubes are arranged between upper and lower headers *f* and *g*, the joint being sealed at each end by means of rubber packing ring *h* surrounded by a sleeve *j* and adapted to be pressed by the end of the collar *e* against the face of the header, the rubber ring being the same diameter as the end of the collar which latter is adapted to enter the sleeve *j* to compress the ring. On the intermediate portion of the tube between the two fixed collars are cooling vanes, shaped and

soldered thereon in a well known manner. In the example shown in Fig. 1 the collar *e* is recessed to receive the end of the tube *a*, and has an extension *k* with restricted passage *m*, such extension virtually forming the end of the tube. In the example shown in Fig. 2 the end of the tube *a* is swaged over at *n* to provide the required restriction. In the example shown in Fig. 3 the collar is arranged as a casting as in the example shown in Fig. 1 with the extension *k* and restricted passage *m*, but having an upper extension *o* fitting into the tube *a* instead of being recessed to receive the end of the tube. As shown in Fig. 4 the collar is similar to that shown in Fig. 1 but the end of the tube is swaged over at *n* as in Fig. 2 to provide the restriction, the extension of the collar itself being relatively unrestricted.

As shown in Fig. 5 the restriction is provided at the upper end of the tube by means of a channel-shaped washer *p*, which is pushed into the end of the tube and secured by solder when the tube is dipped to fasten the vanes or gills.

Obviously it is relatively immaterial at which end of the tubes the restriction is provided so that in each of the above described examples the restriction may be provided at either end of the tube. When provided at the upper end of the tube however, there is the advantage that any obstructions in the water will be caught at the top of the tube or will pass through without lodging therein and will therefore be easily removed.

In use, the tube is fitted by inserting the upper end into the top header when it may be raised far enough to allow the lower end to be brought into register with the correct hole in the lower header. While fitting the tube, the spring may have been previously compressed and secured thus by clips to facilitate the fitting, being released when the tube is in position or may be compressed by the lifting action of fitting the tube. When in position, the spring *d* causes the collars *c* and *e* to be pressed against their respective rubber packing rings *h* which in turn are pressed against the faces of their headers. The sleeves *j* serve to contain the rubber rings.

so that they cannot become displaced or unduly distorted and thus allow a relatively soft and flexible texture of packing to be used, providing an easy and efficient seal which 5 will remain effective under most severe conditions of vibration or mal-alignment. The sleeves also cause the rubber to grip the tube so that a direct seal therewith can be obtained.

10 The packing will preferably be rubber, though other kinds of packing may be used, as the rubber is rendered partly plastic by the heat and adheres firmly to the parts, forming a very effective seal.

15 What I claim is:—

1. A detachable radiator tube, comprising a length of tube provided with jointing means at one end comprising a collar fixed on the end of the tube having a reduced end portion, a relatively long and resilient rubber ring on said reduced portion of a diameter equal to the shoulder formed by such reduction, a sleeve fitting loosely over said collar and rubber ring, and at the other end a collar slidably mounted on the end of the tube, a spring behind same acting to press the collar towards the end of the tube, a relatively long and resilient rubber ring on the said tube of the same diameter as the adjacent 20 part of the collar and a sleeve fitting over said ring and said collar, the ends of the collars in each case engaging the rings being free to enter the sleeves surrounding the rings so as to maintain the pressure, as set forth.

2. In a radiator tube according to claim 1, a fixed collar having a relatively restricted through passage, as set forth.

In testimony whereof I have signed my name to this specification.

40 ALFRED EDWIN HUGHES.
